Inventor:

Earl Abner Reed,

Spear, by Medallion, a. Danielson & Full Attys.

Patented Sept. 14, 1926.

UNITED STATES PATENT OFFICE.

EARL ABNER REED, OF AKEMAH, OKLAHOMA, ASSIGNOR TO BESS L. REED, OF HOUSTON, TEXAS.

ROTARY DEEP-WELL-BORING APPARATUS.

Application filed August 21, 1924. Serial No. 733,410.

The invention concerns the general form of the bit head and the roller cutter organization.

In the accompanying drawings:—

Figure 1 is a vertical sectional view on the line 1—1 of Fig. 2.

Fig. 2 is a bottom plan view.

Fig. 3 is a vertical sectional view on the line 3—3 of Fig. 2, and

Fig. 4 is a view similar to a portion of

Fig. 3, but showing a modification in respect to the mounting of the side roller cutter.

In the drawings a is the main body of the bit head, having side pockets a^4 inclining upwardly and inwardly and in which are located side cutters of known form. The outer overhanging wall of these side pockets is shown at a^1 , in which there is an opening 20 to receive the journal pin of the rotary cutter. These side pockets are at diametrically opposite sides of the bit head. The inner walls of the pockets are indicated at a^2 and these incline downwardly and outwardly 25 from the head. Extending between these inner walls of the pockets and reaching down from the solid body of the head are the walls a^3 , of which there are three. The outer walls of this set connect the walls a^2 30 at the ends thereof. The intermediate wall of the set is parallel with the outer walls, but is unequally spaced in relation thereto. On the outer sides of the outer walls a^3 and formed integral therewith are the pins or 35 studs c which are threaded to receive the retaining and bearing members 4 of the outer rotary cutters 1. The members 4 are shouldered at 4^a and the rotary toothed cutters 1 are shouldered to correspond, so that 40 while the cutters may roll on the members 4, they will be held in place by said members, which are threaded to screw onto the threaded pins or studs c . The cutters 1 are cylindrical and are arranged with their axes 45 at right angles to the vertical axis of the apparatus, and when used with cylindrical rotary cutters in the inclined pockets they will cut a zone overlapping that cut by the said inclined cutters and break down the angular or inclined walls left by the latter.

Rotary cylindrical cutters 2 and 3 are arranged in pairs between the outer walls a^3 and the intermediate wall a^3 , and for affording a journal for these cutters a pin 5 is 50 employed, onto which the cutters are as-

sembled before being placed in the head, and then said cutters with the pin are slipped as one body into place in the walls a^3 . For this purpose the central one of the webs or walls a^3 is formed with a recess or notch a^5 opening clear through its lower edge and the inner faces of the outer webs or walls of the set a^3 are formed with channels or ways a^6 , so that the ends of the pin 5 may slide vertically to a seating at the upper ends of the channels. The notch or recess in the central web is of sufficient height or length to allow the pin 5 to register axially with the axes of the integral side studs or bearings c , and the upper wall of this recess or notch will afford a bearing to receive the up-thrust of the pin. The pin 5 is slotted off or flattened on its sides to bear on the vertical walls of the notch and channels so that some support will be afforded by the engagement of the ends of the flattened pin 5 with the channels, as well as engagement of the pin with the central web. The pin 5 may be held in place in various ways, for instance, by a pin or rod 5^a passing through the integral bearings c and through the webs and of course through the pin 5, and this pin may be held in place by the nuts or bearings 4, the heads of which are closed and adapted to bear on the ends of the pin. The nuts 4 may be suitably formed to receive a wrench, for which purpose they may have exterior socket openings. The main function of this pin 5^a is to hold the bearing 5 from dropping out when the apparatus is lifted from the well. So far as resisting the up-thrust of the central roller cutter organization is concerned, it has no work to perform, because this up-thrust will be borne by the upper wall of the U-shaped notch in the intermediate web or wall, and the upper shoulder a^7 of the channel in the inner faces of the side webs or walls a^3 .

This bit has the advantage of eliminating wear that occurs in existing forms of roller cutter organizations at the ends of the cross roller pin. The bit head above described is rugged and the cutters, not being housed in the head, will permit successful use in formations like lime, that in those forms of apparatus having housed cutters, causes packing of the material and chocking of the cutters against rotation.

The cutters may be either of cylindrical shape, or conical. The bearing 4 may be 110

- either cylindrical or conical. The side cutters may be arranged in pockets of the head, as above described, and have their journal pins supported at both ends in the walls of the pockets, or these side cutters may be supported on pins, Fig. 4, which are integral with the walls a^2 , the overhanging walls a^1 being omitted, and these integral pins a^8 would project upwardly on an inclination.
- 5 The head would have the usual threaded shank. Two sides of the head would be entirely cut away, as compared with the common type of head. That is to say, there would be no body metal of the head above and overhanging the cutter 1, the line $b-b$, defining the shape and limits of the lateral dimension of the head at this point, and if the side cutters are mounted on the integral pins above described the limits of the lateral dimension of the head here would be defined by the line $d-d$, which is a reduction in respect to that form of head in which the side cutter is carried by a pin supported at its outer end in the overhanging wall a^1 .
- 10 It will be seen from the above that the head has a recess at its lower end defined by the walls a^2 at diametrically opposite points connected by webs a^3 (the two outer ones) which are parallel and which reach down from the main body of the head, and that there is an intermediate wall a^3 and the disposition of these walls and cutters is such that some part of the cutter organization will track with some portion of the web or wall organization, so that no part of the area covered by the lower face of the head will be left uncut, it being noted in this connection that the intermediate web a^3 will be tracked by cutter 3; the right hand web a^3 in Fig. 2 which is located nearer the axial center of the head than its companion a^3 at the left of the figure will be tracked by cutter 2. Wall a^2 will be tracked by the right hand cutter 1. It will be noted also that the right hand cutter 1 is of greater width than the left hand cutter 1; and that the left hand web a^3 will be tracked by the right hand cutter 1. The rectangular web or wall formation at the bottom of the head has cutters both inside and outside of it and the outside cutters are disposed at each of the four sides of the rectangle.
- 15 Provision is made for the flow of flushing water to the cutters, as in common practice, from the central bore of the apparatus through suitable ports.
- 20 The pin 5 need be flattened only at the points where it engages the webs a^3 . At other places it would be cylindrical to afford good bearing for the roller cutters.
- 25 In assembling the cutter organization shown in Fig. 1, the cutters 2 and 3 are first mounted on the pin 5, then this pin is slipped into place in the recess of the central web and the channels of the other webs

and its opening brought into line axially with the openings through the bearing studs c . Then the pin 5^a is slipped into place and the bearings or nuts 4 are assembled with their cutters 1 and these are then placed.

70 The retaining pin 5^a may be substituted by two pins passing through the integral studs and entering recesses in the ends of the bearing pin 5. In this instance the bearing pin would be solid except for the small end portions containing the recesses. These pins would be held in place by the nuts or wear pieces 4, as above described.

I claim:

1. In combination in a rotary deep well drilling apparatus, a bit head having webs or walls projecting down from its lower end on opposite sides of the vertical axis, and parallel with each other, a pin having its ends in channels in the inner faces of said walls and bearing against shoulders at the upper ends of said channels rotary cutters on the pin, and rotary cutters exterior to said walls and substantially in axial alignment with the rotary cutters first mentioned, substantially as described.

80 2. In combination in a rotary deep well drilling apparatus, a bit head having webs or walls projecting down from its lower end and including side walls and an intermediate wall, parallel with the side walls, said side walls having channels in their inner faces and said intermediate wall having a notch or recess, a pin adapted to be slipped into place with its ends in the channels and its middle portion in the notch or recess of the intermediate web roller cutters mounted on the pin on opposite sides of the said intermediate wall, and roller cutters mounted exterior to the side walls, substantially as described.

85 3. In combination in a rotary deep well drilling apparatus, a bit head having parallel webs or walls projecting from its lower end, having thrust shoulders on their inner faces, a pin engaging said shoulders, roller cutters on said pin, said walls having bearing studs on their exterior faces, removable wear members screw threaded onto the said studs, roller cutters on said wear members, and a retaining rod passing through the studs and the pin and held in place by said wear members.

90 4. In combination in a deep well drilling apparatus, a drill bit including a head, a cutter supporting bearing thereon, revolvable cutters on said bearing extending diametrically across the center of one end of the head, cutters supported by spin-dles integral with the head, co-axial with the said bearing extending diametrically across the center of one end of the head, and in the same horizontal plane therewith, and side cutters revolvable in planes converging in the head.

5. In combination, a bit head having projecting parallel walls, a bearing pin between said walls, rotary cutters thereon, integral studs on the exterior of the walls, roller cutters thereon, means extending through said studs for holding the bearing pin, and means on the studs for retaining said means and the rotary cutters on said studs.

6. In combination, in a deep well boring apparatus, a head, side walls, and an intermediate wall projecting downwardly from said head, said intermediate wall being slotted

and said side walls having abutments or shoulders, a member fitted to the slot of the intermediate wall and bearing upon the shoulders of the side walls to sustain upward thrust, rotary cutters on said member between the side and intermediate wall and on each side of the latter, means for holding the said member in place and rotary cutters 20 outside the side walls, substantially as described.

EARL ABNER REED.
